Walter H. Kelly

UNITED STATES PATENT OFFICE.

BENJAMIN E. GETCHELL, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

MOUNTING FOR ELECTRIC SWITCH AND PANEL BASES.

Application filed March 8, 1920. Serial No. 364,005.

To all whom it may concern:

Be it known that I, BENJAMIN E. GETCHELL, a citizen of the United States of America, residing at Plainville, Hartford County, Connecticut, have invented a new and useful Mounting for Electric Switch and Panel Bases, of which the following is a specification.

It is customary to mount electric switches, fuses and other fixtures on bases formed of insulating material, such as slate, and to support these bases in metal boxes or containers. With the constructions ordinarily employed the bases are frequently broken or cracked in assembling or in transportation. The main object of my invention is to provide a simple and economical form of construction which will avoid these difficulties.

In its preferred form the invention contemplates the provision of a series of raised bosses carried by the box and fitting into corresponding recesses in the insulating base and screws passing through the insulating base and seated in these bosses. These bosses or parts of them are formed separately from the box and are suitably secured thereto.

Figure 1 is a cross sectional view of a fragment of a box, showing an insulating base held in position by a single screw, and also showing the position for another screw. It will be observed that ordinarily four or more bosses and screws will be provided;

Figure 2 is a plan view of one corner of a box, showing a single boss;

Figure 3 is a bottom view of the same;

Figure 4 is a sectional view of one of the bosses;

Figure 5 is a sectional view of the insulating base, taken through one of the screw passages and recesses for a boss;

Figure 6 is a perspective view of one form of boss before assembling it and securing it in the base;

Figure 7 is a sectional view of a modified form of boss attached to a fragment of a box;

Figure 8 is a bottom view of the same.

The box 10 may be of any suitable construction, ordinarily sheet metal.

The insulating base 11 is designed to carry any form of switch or fuse mechanism or other electrical appliances.

Each boss, such as 12, is formed separately

from the box, and is preferably curved on its upper surface so as to fit into a curved recess 13 in the underside of the insulating base 11.

A series of screws, such as 14, are adapted to secure the base in position, each screw passing through a hole 15 in the base and threading into a tapped hole or seat 16 in the boss 12. To prevent the boss from rotating a part of it, such as 17, may be angular in form and located in a correspondingly-shaped recess 18 in the back of the bottom of the box. A part of the bottom of the box may be raised, as at 19, to form a part of the curved supporting element engaging the curved recess or seat 13 in the insulating base. The boss may be conveniently formed from a blank, such as shown in Fig. 6, where the portion 12' is adapted to be projected through an opening in the bottom of the box and spun over or upset into the form shown in Figs. 1 and 4.

The above construction serves to support the insulating base at a plurality of points, with a space 20 between the base and the bottom of the box. This facilitates the assembling of a base in a box by accurately locating the proper relative position, so that the screws can be readily inserted and seated. This construction also securely holds the insulating base in position in the box without straining the base or tending to chip or fracture it in case force is applied, tending to displace the base with respect to the box.

In Figs. 7 and 8 I have shown a modification in which all of the boss 12' is formed by the inserted member, which is held from rotation by one or more angular projections, such as 17', engaging the bottom 10' of a box.

I claim:

1. In a construction of the character described, the combination of a box, a plurality of raised bosses formed separately from the box but secured thereto and spaced apart from each other, an insulating base having curved seats co-acting with said bosses, and screws passing through said base and screwed into said bosses for securing the base to said box.

2. In a construction of the character described, a combination of a box, a plurality of separately formed bosses having curved

bearing surfaces, means for securing said bosses in said box, an insulating base having seats corresponding with and engaging said bosses to position said base in said box and prevent lateral shifting of said base in said box and screws passing through said base and engaging in said bosses to hold the parts together.

3. In a construction of the character described, the combination of a box having raised portions extending inwardly from the bottom of the box, a separately formed member secured to each raised portion and having a screw seat, an insulating base having recesses fitting on said raised portions and

having holes in line with said recesses, and screws passing through said holes into said screw seats for securing the base to said box.

4. In a construction of the character described, a metal box, a plurality of separately formed bosses having curved surfaces secured to said box, an insulating base having a plurality of recesses corresponding substantially in shape to the curved surfaces of the bosses and means for securing said base to said box with the corresponding bosses and recesses engaging with each other to position the base in the box.

BENJAMIN E. GETCHELL.
